UNITED STATES PATENT OFFICE.

JULIAN MAGRUDER, OF FALLS CITY, OREGON.

CLEANING UTENSIL.

1,115,222.

Specification of Letters Patent. Patented Oct. 27, 1914.

Application filed April 6, 1914. Serial No. 829,849.

To all whom it may concern:

Be it known that I, JULIAN MAGRUDER, a citizen of the United States, residing at Falls City, in the county of Polk and State of Oregon, have invented certain new and useful Improvements in Cleaning Utensils, of which the following is a specification.

My invention relates to improvements in cleaning utensils, and refers particularly to a household article or utensil adapted for service in cleaning dishes or kitchen articles after the manner of a hand mop.

One object of my invention is the provision of an article of this character which will be clean and sanitary by reason of the fact that it will permit the application and removal of the cloth or fabric used for cleaning, thus insuring clean material for service in connection with the utensil.

Another object of my invention is the provision of an article of this character which will be of the simplest and cheapest construction possible, which will be sanitary and thoroughly efficient, and which will be entirely practical from every standpoint.

With these objects in view, my invention consists of a cleaning utensil of the character and for the purpose stated, made from a single piece of wire and embodying novel features of construction, combination and arrangement of parts, substantially as disclosed herein.

Figure 1 represents a perspective view of a cleaning implement or utensil constructed in accordance with and embodying my invention, and Fig. 2 represents an edge view of the implement showing the mop or cleaning material applied to show the manner of using the implement.

My implement or utensil is of extremely simple construction, being made from a single piece of wire bent to the proper shape and consisting of the retaining loop or bend A, the arm B leading therefrom, the end loop or ring C, the intermediate loop or ring D, the smaller loop or ring E, said rings C and D, passing around the arm B, to connect and brace the parts, and the small ring E having the arm F, passing under the retaining loop A, and said arm being bent or twisted to form the head of my device which comprises the series of three rings G, each

composed of two members H, to form a clamp to retain the material J forming the mop or cleaner, and the latter loop passing 55 through the loop A, as at K and retained in place by said retaining loop A. In applying the mop to the handle, the strands of the mop are passed or "threaded" in between the adjoining portion of the loops and because 60 of its resiliency, the metal wire of which the loops are made, clamps and holds the mop in place. From this construction, it will be observed that the implement consists of a handle or grasping portion and a head portion 65 composed of a series of clamping members or rings which grasp and retain the material which forms the mop or cleaner, and for the purpose of conveniently suspending the implement, I provide the hook 70 L, which is connected to the device as shown.

It will be seen that by bending the wire as shown the handle is made strong and stiff and, the end ring and intermediate rings serve to brace and strengthen the handle 75 while the series of three double rings make a mop carrying head of angular shape the double rings receiving and clamping the fabric between the two strands which comprise each ring. The angular shape of the 80 clamping head is important as the upper pair of rings give a broad portion to clamp the fabric while the outer ring narrows the head and enables the fabric to enter small places and edges to effect a more perfect 85 cleaning.

It will be understood that I provide a device which can be manufactured at a very small price, which is sanitary and healthful for the purpose intended, and which will 90 prove a useful and practical household article.

I claim:

1. The cleaning implement herein described, made from a single piece of wire 95 and consisting of a handle or grasping portion having an end ring and a series of intermediate bracing rings, and a head adapted to receive and hold the mop or cleaning material and consisting of a series 100 of double strand clamping rings.

2. The cleaning implement herein described, consisting of a handle or grasping portion provided with an end ring and a

series of connecting and bracing rings, a head of triangular form comprising a series of clamping rings for securing the cleaning material, said rings being disposed to form a forward single ring and an upper pair of rings, and a terminal hook for securing the rings to the handle.

In testimony whereof I affix my signature in presence of two witnesses.

JULIAN MAGRUDER.

Witnesses:

A. J. VICK,
W. F. NICHOLS.
